UNITED STATES PATENT OFFICE.

ANDREW H. LUCAS, OF ST. LOUIS, MISSOURI.

VELOCIPED.

SPECIFICATION forming part of Letters Patent No. 391,417, dated October 23, 1888.

Application filed June 29, 1888. Serial No. 278,538. (No model.)

To all whom it may concern:

Be it known that I, ANDREW H. LUCAS, a citizen of the United States, residing at St. Louis, in the State of Missouri, have invented 5 a new and useful Improvement in Velocipedes, of which the following is a specification.

My invention relates to an improvement in velocipedes; and it consists in the peculiar construction and combination of devices, that will 10 be more fully set forth hereinafter, and particularly pointed out in the claims.

In the accompanying drawings, Figure 1 is a side elevation of a velocipede embodying 15 my improvement. Fig. 2 is a top plan view of the same. Fig. 3 is a vertical transverse sectional view taken on the line $x-x$ of Fig. 2.

A represents the backbone, which is raised near its rear end and provided with a saddle, B, in which and in the rear portion of the 20 backbone is a vertical longitudinal slot, C, of suitable width. From the rear end of the saddle depends a curved arm or standard, D, the lower end of which is provided with horizontal transverse bearings E, in which is journaled the rear shaft, F, of the velocipede. To 25 the ends of the said shaft are secured the rear wheels, G, and to the center of the same is secured a spur-pinion, H.

I represents the front axle, which is pivotally connected to the front end of the backbone, and on the ends of which are journaled 30 the front wheels, K. Arranged above the said front axle, parallel therewith and connected thereto, is a steering-lever, L.

M represents a large spur-wheel, which is arranged in the slot C, and is journaled on a shaft or spindle, N, which is secured in the 35 sides of said slot. This spur-wheel meshes with the pinion H, and is provided on one side 40 with a series of radial arms, O, which are at

suitable distances apart and have balls or handles P at their outer ends, whereby they may be conveniently grasped by the rider.

The operation of my invention is as follows: The rider seats himself upon the saddle and places his feet on the ends of the steering-lever, and grasps each handle or arm O of the wheel M in succession and rotates the said wheel in the direction indicated by the arrow in Fig. 1, thereby causing accelerated rotation 45 to be imparted to the rear shaft by means of the pinion H, and consequently causes the velocipede to be impelled very rapidly and with comparatively slight exertion.

Having thus described my invention, I 55 claim—

1. In a velocipede, the combination of the backbone having the integral rear depending standard, D, and the slot, the rear axle journaled in said standard and having the gear-wheel H arranged in the slot, the gear-wheel 60 M, arranged in the slot, having its bearings in the backbone and meshing with the wheel H, the handles P, projecting radially from the wheel M, and the saddle supported on the 65 backbone, substantially as described.

2. In a velocipede, the frame, the saddle, the axles journaled in the frame, the wheel H on one of said shafts, and the wheel M, journaled in the frame, engaging wheel H and 70 having the radial projecting handles, substantially as described.

In testimony that I claim the foregoing as my own I have hereto affixed my signature in presence of two witnesses.

ANDREW H. LUCAS.
